UNITED STATES PATENT OFFICE.

JOHN I. MISENER, OF SYRACUSE, NEW YORK.

HAMMER ATTACHMENT FOR ELECTRIC DRILLS AND THE LIKE.

Application filed August 10, 1925. Serial No. 49,479.

My invention relates to hammer mechanism, and has for its object a particularly simple hammer attachment for electric drills and the like, which can be quickly and easily attached and detached and is highly efficient and durable in use.

The invention consists in the novel features and in the combinations and constructions hereinafter set forth and claimed.

10 In describing this invention reference is had to the accompanying drawings in which like characters designate corresponding parts in all the views.

Figure 1 is a side elevation partly in section of an electric drill with my hammer attachment fixed thereto.

Figure 2 is a face view of one of the lifting cams.

Figure 3 is a sectional view taken on line 20 3-3, Fig. 2.

Figure 4 is a longitudinal sectional view of the reversible collar for holding the tools.

Figure 5 is an end elevation of the collar 25 shown in Fig. 4.

Figure 6 is a sectional view taken on line 6-6, Fig. 1.

My invention comprises generally, an electric drill including the usual revolving chuck 30 and a body portion for supporting said revolving chuck, hammer mechanism including a casing and a reciprocating head, means for attaching the casing of the hammer mechanism to the body portion of the electric drill, and means for connecting the reciprocating head to the revolving chuck for operating said reciprocating head.

In the drawing 1 represents an electric drill of any well known type, having the 40 usual frame or body portion 2 enclosing an electric motor, and the usual chuck or tool holder 3, mounted on the power shaft 4 of said electric motor.

The hammer mechanism as here shown 45 comprises a casing 5, and a reciprocating hammer head 6 mounted therein.

The casing 5 as here shown is cylindrical in general form and the front end 7 of the body 2 of the electric drill is circular and is 50 formed near said front end with a shoulder 8. The rear end of the casing 5 fits over said front end and abuts against the shoulder 8 and is secured thereto as by the screws 9.

55 Any other desirable means of fastening the casing of the hammer mechanism to the

body portion of the electric drill may be used.

The front end of the casing 5 as here shown is formed with an inturned flange 10 and a member 11 is seated therein and is formed with a reduced threaded collar 12 extending through said front end and with an axial passage 13 extending therethrough forming a bearing for the hammer head 6. 60

The inner end face of the member 11 is formed with teeth 14 around the passage 13, said teeth providing cam surfaces 15 to be hereinafter described.

The hammer head 6 extends through the 70 passage 13 and as shown in Fig. 1, is formed with an enlarged portion 16 intermediate its ends and said enlarged portion is formed with teeth 17 having cam surfaces coacting with the cam surfaces 15 on the part 11. 75

The enlarged portion 16 of the hammer head 6 is preferably made separate from the shank thereof and as here shown is fixed thereto by the pin 18. The inner end thereof is preferably recessed as at 19, and a 80 compression spring 20 is interposed between the bottom of the recess portion 19 and the chuck 3.

21 is a power shaft which is clamped in the chuck 3 in place of the usual drill and in 85 the same manner.

I have here shown the inner end of the hammer head 6 as being counterbored and formed with a lengthwise slot 22 extending diametrically therethrough. 90

The outer end of the power shaft slidably fits said counterbore and is provided with a pin 23 which coacts with the slot 22, thereby forming a slidable connection between the power shaft 21 and the hammer head. 95

The coacting teeth 14 and 17 on the member 11 and the head 16 provide a means for moving the hammer head 6 in one direction as for instance the up or rise stroke of the hammer, and said rise stroke is against the action of the spring 20. The back of the teeth 14 and 17 being cut approximately parallel with the movement of the hammer head provides the fall or down stroke of the hammer and the force of said down stroke is 100 determined by the compression of the spring 20. 105

As will be obvious to those skilled in the art the number of teeth or cam surfaces on the coacting backs will determine the number of strokes per revolution of the power shaft. 110

I have here shown four teeth on each of the coacting parts, but obviously any desirable number may be provided.

For convenience of manufacture and assembling the part 11 is held from rotation with respect to the casing 5 by means of the spring pressed dowel pins 24 coacting with aligned holes in the inturned flange 10, and as shown in Fig. 1, is locked in position by means of the tool holder 25 which threads upon the reduced collar 12 of the part 11 and against the inturned flange 10 of the casing.

In tools of this description the hammer head does not as a rule act directly upon the work, but acts upon a tool as for instance the tool 26 which is here shown as a star drill having a hexagonal shaped or six sided shank. When using a tool in the holder 25 of the type illustrated it is desirable that the tool should change its striking point at every blow of the hammer, while with other types of tools it is essential that the tool used in the holder does not change its striking point.

In my invention I have provided a construction whereby simply reversing the position of one member, the tool will have an axial movement or will not have an axial movement.

27 is the reversible member and as shown in Figs. 1, 4 and 5, comprises a sleeve fitting within the tool holder 25, the inner diameter of one end as 28 being round approximately one-third of its length and slidably fitting the outer diameter of the shank of the hammer head 6. The rest of the sleeve on the inside is cut hexagonal or out of round, as shown at 29, with the corners thereof a continuation of the inner diameter of the round portion 28. The outer end 30 of the hammer head 6 extends into the sleeve 27 and is formed hexagonal to fit the hexagonal portion 29 thereof. The shank of the tool 26 also fits the hexagonal portion 29.

In Fig. 1 the hexagonal or out of round portion 29 of the sleeve 27 is turned in toward the hammer head, therefore both the end 30 of the hammer head and the end of the tool 26 are in the hexagonal portion of the sleeve, therefore the sleeve and consequently the tool 26 will be turned when the head is operated.

When the sleeve 27 is reversed that is turned end for end, the round portion 28 of the sleeve is on the hexagonal portion 30 of the hammer head, obviously neither the sleeve nor the tool 26 will be turned.

The sleeve is held in place by the screw cap 31 which is provided with a packing 32 to prevent dust and dirt from getting into the hammer and to prevent grease from leaking out. 33 is a grease plug for supplying grease to the hammer attachment.

This hammer attachment is the reverse of the hammers now in use, as when the operator wants to strike a very light blow, he forces the tool as close to the work as possible and when he desires a heavier blow he lets up on the pressure.

What I claim is:

1. A hammer mechanism comprising a casing, a tool holder fixed to one end of said casing, a revolving and reciprocating head in said casing having one end thereof extending into one end of said tool holder and provided with a non-circular portion, a tool having a noncircular portion extending into the other end of said tool holder, and a reversible means arranged in said tool holder to coact with the non-circular portions of the reciprocating head and the tool to turn the tool when the head reciprocates, or to coact with only one of said non-circular portions, whereby the tool does not turn when the head reciprocates.

2. A hammer mechanism comprising a casing, a tool holder fixed to one end of said casing, a revolving and reciprocating head in said casing having one end thereof extending into one end of said tool holder and provided with a noncircular portion, a tool having a noncircular portion extending into the other end of said tool holder, and a sleeve having a circular portion and a noncircular portion reversibly mounted in said tool holder so that the noncircular portion coacts with the noncircular portions of the head and tool or is reversed to coact with only one of said parts.

In testimony whereof, I have hereunto signed my name, at Syracuse, in the county of Onondaga, and State of New York, this 18th day of July, 1925.

JOHN I. MISENER.
